OFFSHORE TANKER LOADING AND UNLOADING APPARATUS
Joseph Siegel, 5 Glen Lane, Port Washington, N.Y.
Filed July 12, 1961, Ser. No. 123,490
4 Claims. (Cl. 9—8)

The present invention relates to improvements in offshore loading and unloading apparatus for tankers carrying oil and other liquid products.

In the loading and unloading of oil tankers, and particularly in the case of large of supertankers, situations exist at many points in which it is necessary to moor the vessel offshore throughout the transferring operation. Under such circumstances it is common practice to employ a flexible hose normally lying on the sea bottom, its inner end being connected to the submarine pipe line of the shore installation and its outer end being provided with a marking buoy. To prepare for a transfer, mooring is first accomplished by utilizing a system of fixed stern and breasting mooring buoys and anchors together with the tanker's own bow anchors, to locate the vessel with the manifold piping in close proximity to the seaward end of the submerged hose as indicated by the marking buoy. The hose is then raised from the sea bottom by means of the tanker's hoisting boom and attached to the ship's piping system. In the raising operation a great deal of time and effort must be expended in detaching the hose buoy and associated equipment from the seaward end of the hose, particularly if the sea condition is other than dead calm. Similarly, after transfer is completed undue amounts of time and effort are involved in re-attaching the hose buoy and related equipment and in returning the hose to the sea bottom free of kinks and stretched in proper position for the next raising.

In the present trend of construction and use of larger and operationally more economical tankers or supertankers, to to speed up transfer and minimize demurrage costs the use of a plurality of large submarine hoses is indicated in order to utilize the tanker's extremely large pumping capacity during unloading, or in the case of loading, to cut the filling time to a minimum. However, the use of such multiple hoses by the above described established practice has proved impractical due to several factors. In the first place, the hoses have tended to become entangled with one another on the sea bottom, requiring the services of a diver to straighten them before they may be raised again to the sea surface without resulting in kinked hose. Also, the previously noted expenditure of time and effort required for detaching and reattaching the hose buoy and related equipment is obviously multiplied. On the other hand, the use of very large hoses in order to minimize their number is confronted with limitation in the tanker's boom hoisting capacity as well as the possible commercial unavailability of such oversize hoses in general manufacturing standards. In view of the above and related difficulties, an object of the present invention is to provide improved transfer apparatus in which the necessity for raising and lowering of the submarine hoses and detachment and reattachment of marking buoys is eliminated.

A further object is to provide improved transfer apparatus adapted to employ any required number of stand-

2

ard hoses without any tendency toward tangling or kinking.

A further object is to provide improved transfer apparatus including a buoyant vessel or pontoon adapted to be located alongside the tanker or supertanker and constituting an intermediate connecting station between the shore installation and the tanker's piping system.

A further object is to provide an intermediate transfer pontoon having piping means normally connected to one or more of the submarine hoses of a shore installation, and carrying flexible hose means located above water at all times and adapted to complete the fluid connection between the shore installation and a tanker's piping system. A further object is to provide an intermediate transfer connecting pontoon including means to increase and decrease the draft of the pontoon in accordance with changes in the tanker's draft during loading and unloading.

A further object is to provide an intermediate transfer connecting pontoon adapted to move in synchronism with the tanker's or supertanker's normal drift, rise and fall due to tide and swells, thus preventing undue stress on the flexible transfer hose and its connections.

A further object is to provide improved fluid transfer apparatus adapted to effect efficient and economical loading of a tanker or supertanker of any given size and pumping capacity by selective or combinational use of a plurality of hoses carried by a common intermediate connecting pontoon.

A further object is to provide improved offshore fluid transfer apparatus including a floating intermediate connecting station adapted to be ballasted to maximum submergence when not in use, thereby reducing to a minimum the amount of its surface exposed to high winds and waves during inclement weather.

Another object is to provide offshore transfer apparatus including means for launching and receiving multi-product dividers in a submarine pipeline installation.

Another object is to provide offshore transfer apparatus including means for purging submarine pipe lines.

A further object is to provide an offshore station including a connecting pontoon structure movable upward and downward on guide piles secured in the ocean bottom.

Other objects and advantages of the invention will become evident during the course of the following description in connection with the accompanying drawings, in which

FIGURE 1 is a diagrammatic plan view of a tanker positioned for loading or unloading by apparatus in accordance with one embodiment of the invention;

FIGURE 2 is a lateral view illustrating the relationship of the tanker and the connecting pontoon structure as shown in FIG. 1 when both are in their positions of maximum submergence;

FIGURE 3 is a view similar to FIG. 2 showing the tanker and pontoon in their positions of minimum draft;

FIGURE 4 is an exterior end view of the connecting pontoon structure;

FIGURE 5 is a longitudinal view of the structure of FIG. 4, partly in section, and illustrating typical arrangements of the piping and hose equipment;

FIGURE 6 is a top view of the structure shown in FIG. 5;

FIGURE 7 is a diagrammatic illustration of the ballast pump connections;

FIGURE 8 is a horizontal sectional view of the pontoon structure in the plane 8—8, FIG. 5;

FIGURE 9 illustrates an "island" type loading and unloading station in accordance with the invention;

FIGURE 10 illustrates in plan view the guiding system for the connecting pontoon structure, shown in FIG. 9, and

FIGURE 11 is a rear or offshore directed view of the embodiment of the invention shown in FIGS. 9 and 10.

Referring to FIG. 1, the numeral 20 designates a tanker moored off the shore 21 on which is situated a petroleum supply or receiving installation such as a tank farm or the like, the seaside piping system of the onshore plant being generally indicated at 22. The tanker is moored by means of a system of permanently located stern and breast-
ing mooring buoys 23 and anchors 24 in combination with the ship's bow anchors 25, the moored position being such as to place the tanker's loading and unloading piping facilities 26 in close juxtaposition with a hose buoy or intermediate connecting pontoon station 27. Underwater pipes 28, 29, and 30 run offshore along the ocean bottom to a point 31 conveniently marked by a spar buoy 32, whence they are connected respectively by flexible hoses 33, 34, and 35 to the floating station 27 in the manner illustrated in FIGS. 2 and 3. Referring to these latter figures, it will be seen that the underwater flexible hoses are connected to risers extending upward through the bottom of the floating intermediate station unit 27, the individual connecting arrangements of all the submarine lines being typified by the connection of the hose 33 from the submarine pipe 28 at point or zone 31 to the corresponding riser 36.

The construction and equipment of the station unit 27 shown in detail in FIGS. 4, 5, 6, 7, and 8, are as follows: The hull or buoyancy element is a pontoon 37 having a water-tight top closure plate 38 (see FIG. 5), above which is disposed a top operating deck 39. The pontoon 38 is constructed with a plurality of transverse bulkheads 40 dividing it, in the present example, into five compartments 41, 41a, 41b, 41c and 41d. A system of vent pipes 42, terminating in upper goose-necks 43, affords open connections from the various compartments to the atmosphere, and the bulkheads 40 are provided with lower openings 43 to permit equalization of the ballast water level in the compartments. The riser pipes 36, 44 and 45, connected respectively to the submarine hoses 33, 34 and 35, extend upward through the bottom of the pontoon, the top plate 38 and the deck 39. The riser pipe 36, which in the present example is of substantially larger diameter than the other two, terminates in an upper header 46 secured in saddles 47 mounted the deck 39. Three vertical loading arm pipes 48, equipped with gate valves 49, extend upward from the header 46 and are surmounted by angular swivel fittings 50 to which are connected lengths of flexible hose 51 adapted to form final transfer connections to the piping system 26 of the tanker or supertanker 20 as illustrated in FIGS. 2 and 3. It will be understood that the valves 49, as well as the other similar valves throughout the assembly are equipped with the usual manual operating handles or wheels 52 as shown in FIGS. 2, 3 and 4, but that the detail showing of such handles is omitted from the diagrammatic representation of the valves in the other figures in order to avoid unnecessary complication in illustration.

The riser pipes 44 and 45 continue directly upward as individual loading arm pipes 53 and 54, equipped with valves 55 and 56 respectively and topped by swivel fittings 50 to which are attached final connecting hoses 57 and 58. A horizontal cross-over pipe 59, provided with a valve 60, is adapted to effect a transfer connection between the loading arms 53 and 54 when desired. Also connected into the arm 53 is a valved lock structure 61, FIG. 8, for use in launching and receiving multi-product pipeline dividers.

A ballast pumping assembly 62 is mounted on the deck 39 as shown in plan in FIG. 6. This assembly, which is adapted to effect any desired change in the amount of ballast water contained in the pontoon 37 in order to adjust the latter's degree of submergence, consists of a pump 63 provided with a driving motor 64, an alternatively suction or delivery pipe 65 extending down within the pontoon hull, overboard suction and discharge pipes 66 and 67, and a flow-reversing arrangement which may best be understood in connection with diagrammatic FIG. 7. Referring to FIG. 7, it will be seen that the suction end 68 of the pump 63 has two alternative connections, namely via a gate valve 69 with the overboard suction pipe 66 or via a second valve 70 and a branch pipe 71 with the interior pipe 65. Similarly, the discharge end 72 may alternatively be connected via a valve 73 to the overboard discharge pipe 67 or via a valve 74 to the interior pipe 65. Thus by opening valves 69 and 74 while closing 70 and 73, the pump 63 will be caused to deliver water from the ocean into the pontoon through the interior pipe 65; similarly, when valves 70 and 73 are opened while 69 and 74 are closed, water will be withdrawn from the pontoon through the pipe 65 and discharged overboard. It will further be evident that if desired, by adjustment of the various valves a partial bypass or feedback flow may be set up between the discharge and suction ends of the pump, thus in effect varying the latter's pumping capacity so as to regulate the pontoon's rate of submergence or emergence independently of the pump's normal speed and maximum delivery rate.

During periods when the final connecting hoses 51, 57 and 58 are not in use their outer ends are retained by means of their attaching fittings 75 on closure spuds 76 secured on the deck 39, as shown in FIGS. 4, 5, and in dot-and-dash lines in FIG. 2. The end fittings of the hoses also include hoisting eyes 77 to accommodate the hook or hooks of the tanker's hoisting equipment when a transfer connection is to be made. Cleats 78, secured to the deck 39, are provided for the attachment of ship's lines in order to prevent spread, due to drift, between the tanker and the intermediate or pontoon station in the event of sudden unduly high tidal wave motion. Other exterior fittings of the pontoon 27 include a series of vertical fenders or bumpers 79 disposed on the sides and ends of the hull, a guard rail 80 around the deck 39, FIG. 6, and a boarding ladder 81. Four lugs 82, projecting from the V bottom of the pontoon hull near the outer corners thereof, are fitted with shackles 83 for attachment of chains 84 leading to fixed anchors 85 on the sea bottom 86, as shown in FIGS. 2 and 3.

A typical transfer procedural operation is as follows: Assuming first that a tanker or supertanker 20 is to be unloaded to shore, the ship is moored with the pontoon station 27 alongside in proper location as previously set forth in connection with FIG. 1, ship's lines 88 (FIG. 6) being attached to the cleats 78 as noted above. Since the tanker 20 is initially loaded, it rides low in the water as illustrated in FIG. 2. Accordingly, the pontoon hull 37 initially is heavily ballasted with sea water by means of the pumping assembly 62 so as also to lie low in the water as shown. The final connecting hoses 51, etc., are detached from their supporting spuds 76, hoisted and attached to the tanker's piping system. Whether all the hoses 51, etc., or only part of them are so used is determined by the number required to utilize to best advantage the maximum pumping capacity and to match the piping system of the particular supertanker or smaller vessel to be unloaded. The hose connections having been completed, the corresponding valves 49 are opened and the tanker's cargo is pumped downward through the pontoon station's previously described internal piping to the permanently connected submarine hose and piping system and thence to the shore establishment 22. As the unloading progresses the ballast water in the pontoon 37

is reduced by means of the pumping assembly 62, increasing the effective buoyancy of the entire intermediate connecting unit 27 so that it rises in concert with the increased emergence of the tanker until the latter's final unloaded situation is reached as illustrated in FIG. 3. The upward movement of the unit 27, together with the yielding swing of the swivels 50, reduces the necessary flexing of the final connecting hoses to a minimum, increasing durability and permitting the hose units to be of relatively short length and consequent light weight.

It will be noted that during the foregoing operation the upward flexing of the submarine hoses 33, etc., is accomplished by the buoyancy of the pontoon 37 rather than by any direct connection with the tanker's equipment. Thus the interposition of the pontoon station 27 relieves the final connections to the tanker of all stress except that necessary to support the relatively light hoses 51 and their fluid content. Similarly, the ship's boom hoisting equipment in effecting the initial pumping connections is required only to hoist the ends of the hoses 51 from the deck level of the pontoon station 27, irrespective of how large, heavy or numerous the submarine hoses may be. In the latter respect, the provision of the header or manifold 46 on the pontoon station, FIG. 5, permits the submarine hose 33 connected thereto to be of a large size which in prior practice would be beyond the hoisting capacity of the tanker's equipment, but which latter equipment in the present invention has only to deal with the smaller standard those sections 51, as noted. The optional use of larger submarine hoses and pipes in turn allows them to be fewer in number to provide a given maximum transfer capacity, thus reducing both initial and maintenance costs, while at the same time the diversification of final connections provided by the intermediate pontoon station renders the system flexibly adapted to serve all sizes of tankers with maximum efficiency. The factor of efficiency obviously includes the ease and quickness of connecting the hoses 51 to the tanker's piping system 26 and their final disconnection at the completion of transfer, both of which operations are conducted entirely above water, eliminating the hitherto laborious and time consuming necessity for dragging up separate submarine hoses, disconnecting them from buoys and subsequently re-connecting them thereto. The fact that except for long-term repairs or replacements, the submarine hoses remain attached to the pontoon station 27 and at all times prevent any tangling or kinking of these hoses.

The procedure in loading a tanker from shore generally parallels that described for unloading, except that the initial positions of the tanker and pontoon station 27 are as shown in FIG. 3, the pontoon station thereafter being ballasted to greater submergence by means of the pumping equipment 62 as the loading progresses to the final relation shown in FIG. 2. Current supply for the motor 64 of the pumping equipment may be derived either from the tanker's electric system or via suitable waterproof cable from the shore station, the latter arrangement being generally preferred as it renders the motor operation independent of possible voltage or other differences in available current supply from various tankers, as well as permitting operation in the absence of any tanker. If found desirable in certain station locations, the motor 64 may be replaced by a suitable internal combustion engine, thus rendering the ballast pumping system a completely self-contained unit.

In addition to the described advantages of the invention in effecting loading and unloading operations, the interposition of the pontoon station 27 allows the provision of means to carry out transfer and maintenance operations hitherto not feasible in conventional offshore installations. For example the valved lock structure 61, FIG. 6, permits the introduction and reception of multi-product dividers at the extreme outer end of the transfer system, with advantages obvious to those skilled in the

art. Similarly, valved cross connections such as 59—60, FIG. 5, provide for ready transfer of fluid from one pipe line to another, and in combination with the shore station's pumping apparatus, facilitate the purging of the pipe lines, including the submarine hose and piping portions, of obstructions such as heavy wax accumulations.

In the "island" type of loading and unloading station shown in FIG. 9 the tanker 20 is tied up to a series of permanent offshore mooring platforms 87, the latter being built up from the ocean bottom to a level above mean high tide. Adjacent platforms at the ends of the series are provided with bridges 88 to facilitate the mooring and cast-off operations. With this type of installation the floating intermediate or pontoon station 27 may be located 10 by the alternative means illustrated in FIGS. 10 and 11 instead of by chains and anchors as in FIGS. 2 and 3. The locating and guiding means in this case consists of a suitable pattern of piles 89, preferably of H-beam section, which have been driven and rigidly fixed in the ocean bottom 86. Runners 90, secured to the pontoon 37, loosely engage the piles 89 in vertical guiding relation, so that the pontoon station is free to rise and fall in response to tidal changes and changes in its own ballast condition as 15 previously described. It will be understood that the deck equipment, piping, underwater hose connections, and mode of operation of the intermediate connecting station 27 are the same as those previously explained and therefore need not be further described herein.

In both types of locating arrangement of the pontoon 20 station, the latter may be ballasted to maximum submergence during periods between transfer operations, thus presenting minimum upper area to winds and wave action 30 in case of inclement weather; this is obviously an addition to the normal operational advantages of the ballast pumping equipment 62.

In the foregoing description the pontoon station 27, which provides efficient shipside procedures hitherto not attainable in offshore loading and unloading operations, the station has been shown with three submarine connecting lines and five above-water final connecting lines, 40 three of the latter being branched from the header 46. It will be obvious, however, that the pontoon station may be built with any other desired piping and hose combination called for by particular shore station situation and 45 range of tankers to be served, the same applying to the number and arrangement of cross-over connections or manifolds exemplified by 59—60, FIG. 5, as well as to the facility provided by the deck 39 for the mounting of such auxiliary equipment as meters, gauges, and the like 50 at substantially the immediate point of transfer. Thus, while the invention has been described in preferred form, it is not limited to the precise embodiments illustrated, as various modifications may be made without departing from the inventive concept within the scope of the 55 appended claims.

What is claimed is:

1. In apparatus for transfer of fluid between a marine tanker moored at a predetermined offshore location and a shore station having submarine piping directed toward 60 said offshore location, in combination, an intermediate connecting station retained offshore in close proximity to said tanker location including a hull with a vertical side structure adapted to operationally abut a side of said tanker in vertically and horizontally guided relation 65 throughout a substantial area of said tanker side and further including a piping system secured to said hull, means to raise and lower said intermediate station in operative concert with changes in draft of said tanker, means to secure said hull to said tanker side in said abutted guided 70 relation, yieldable submarine transfer means connecting said submarine piping to said piping system of said intermediate station, and flexible hose means carried above water by said intermediate station and adapted to be attached to the piping system of said tanker for connecting the same 75 to said piping system of said intermediate station, where-

by fluid transfer communication may be completed between said tanker and shore establishment through said intermediate station.

2. Apparatus according to claim 1 wherein said hull comprises a structure having essentially vertical side walls, a bottom wall and a top wall, and a top deck spaced above said top wall, the space between said top wall and deck being open to permit the free flow of water therethrough when the top wall is approximately at or below the water surface. 10

3. Apparatus according to claim 2 wherein said bottom wall is of V-shaped section.

4. Apparatus according to claim 2 wherein said hull includes internal partitions and said means of raise and lower said station comprises a selectively controlled pump 15 for pumping water into and out of said hull.
